UNITED STATES PATENT OFFICE

RAY PERCY SMITH, OF PENOKEE, KANSAS

INTAKE MANIFOLD

Application filed July 16, 1930. Serial No. 468,398.

The present invention relates to internal combustion engines, and has more particular reference to an improved manifold construction.

An object of the present invention is to provide an improved manifold of this type by means of which the mixture from the carburetor may be properly and equally distributed to the various intake openings of the engine block, and so that the suction in the manifold will be uniform throughout its entire length and branches, and so that the remote cylinders at opposite ends of the block will be supplied with the relatively adequate amount of the charge.

A further object of this invention is to provide an intake manifold for internal combustion engines by means of which economy in consumption of fuel will be effected, which will better the operation of the engine, which will increase the speed and horse power of the engine relative to the amount of fuel consumed and which will provide easier starting of the engine during all seasons of the year.

The invention also aims at the provision of an intake manifold embodying the above pointed out characteristics, and which is of such construction that it may be readily substituted for manifolds at present in use without requiring change in equipment or modifications in the construction of either the carburetor or the engine block.

With the foregoing and other objects in view, the invention will be more fully described hereinafter, and will be more particularly pointed out in the claim appended hereto.

In the drawings, wherein like symbols refer to like or corresponding parts throughout the several views,

Figure 1 is a top plan view of a central block having a manifold constructed according to the present invention applied thereto, and

Figure 2 is a side elevation of the same, parts being shown in section.

Referring to the drawings 10 designates a cylinder block of any suitable construction or configuration and which for the purposes

of disclosure is shown in the present instance for a six cylinder internal combustion engine.

The intake passages 11 are shown in dotted lines at one side of the block and are three in number, each passage 11 leading to two adjacent cylinders and opening to the intake ports or valves thereof and the passages 11 opening at three spaced points alongside of the block 10 in the usual manner.

The manifold of the present invention comprises a horizontal or straight line section 12 of substantially pipe form, and which is provided at each end and at an intermediate point with a coupling nipple 13 terminating in an attaching flange 14 adapted to be secured by bolts 15 or the like to the side of the cylinder block 10 in registr, with the respective intake passages 11. The horizontal section 12 is provided intermediate its ends with a vertically disposed branch 16 communicating with the horizontal section 12 and of substantially the same diameter as the same and opening into the branch adjacent to the intermediate nipple 13. The horizontal section 12 is also provided at opposite ends with intercommunicating upwardly converging or inclined branches 17 of the same diameter as the horizontal branch 12, and which open into the ends of the branch 12 adjacent to the end nipples 13. The branches 17 converge upwardly and merge at their upper ends into the upper end of the vertical section 16 and intercommunication therewith. The three branches 16 and 17 open into an elbow coupling section 18, which is overturned and provided at its free downwardly opening end with an attaching flange 19 to which the flange 20 of a carburetor 21 is secured by bolts 22 or the like.

The manifold thus constructed is of the top feed type wherein the mixture from the carburetor 21 is carried upwardly and over through the elbow 18 into the top of the manifold and from the elbow 18 is drawn by equal pressure downwardly through the diverging end branches 17 and the vertical central branch 16 into the lower horizontal section 12 at the inner ends of the respective nipples 13. Should there be an unequal pres-

sure at the intake nipples 13 the cross, horizontal or intercommunicating branch 12 establishes a suitable connection between the nipple for equalizing the pressure at the same and insuring the proper and even supply of the mixture to all three of the nipples 13.

While the manifold has been disclosed in the present instance in connection with a six cylinder engine, it is to be understood that 10 the construction may be so modified and arranged as to adapt the manifold to engines of a greater or lesser number of cylinders. It is important that there be a direct lead from the carburetor connection to the individual supply nipples 13, and that there also be a cross connection between the nipples so as to equalize the pressure throughout the manifold and insure the proper and even distribution of the fuel charge.

20 It will be noted that a down draft intake manifold is provided wherein the diverging branches 17 communicate with the outer ends of the main body or cross portion 12 and also intercommunicate with the upper end of the 25 vertical branch 16 at a point near the elbow 18.

Referring now to Figure 1 it will be noted that the gaseous mixture is drawn directly 30 down to the forward cylinders 1 and 3 through the forward branch 17 and to the rear cylinders 5 and 6 through the rear branch 17, the intermediate or central cylinders 2 and 4 being supplied with the mixture through the vertical branch 16 directly from the elbow 35 18.

As is at present the case without the use 40 of the upwardly converging end branches 17, the forward and rear cylinders receive less of the gaseous mixture than is received by the central cylinders. Further, the central cylinders 2 and 4 receive a richer and more thoroughly carburetted mixture than the outer cylinders with the result that the smooth running of the motor cannot be had and consequently the vibration of the motor is increased.

It will also be noted that with the construction disclosed by the present invention when 50 the motor is not running the mixture will be permitted to remain in the conduits 12 and 17 for a considerable length of time and that, therefore, the engine may be easily started incident to this accumulation of the charge in the manifold beyond the carburetor and immediately adjacent to the intake passages 11.

I do not wish to be restricted to the size, form, and proportions of the various parts, and obviously changes could be made in the construction herein described without departing from the spirit of the invention, it being only necessary that such changes fall within the scope of the appended claim.

What is claimed is:—
60 A down draft intake manifold for internal combustion engines, comprising a horizontal

pipe section having end and intermediate coupling branches adapted for attachment along the side of an internal combustion engine for communication with the intake passages thereof, a plurality of pipe branches of substantially the same diameter as said horizontal pipe connected thereto in registry with said coupling branches and converging upwardly to a point above the horizontal pipe and merging together in intercommunicating relation, and means at the point of emergence of said pipe branches for connecting a carburetor thereto.

In testimony whereof, I have affixed my signature.

RAY PERCY SMITH.
